OHIO, ASSIGNEES TO AMERICAN STEEL FOUNDRIES, OF NEW YORK, N. Y., A COR-
PORATION OF NEW JERSEY.

COUPLING-KNUCKLE REINFORCEMENT.

1,135,528.

Specification of Letters Patent. Patented Apr. 13, 1915.

Application filed October 25, 1912. Serial No. 727,846.

To all whom it may concern:

Be it known that we, ROBERT E. L. JANNEY, of Chicago, in the county of Cook and State of Illinois, and EDMUND P. KINNE, of Alliance, in the county of Stark and State of Ohio, citizens of the United States, have invented certain new and useful Improvements in Coupler-Knuckle Reinforcements, of which the following is a specification.

10 Our invention relates to car couplers and has particular reference to a novel coupler knuckle reinforcement.

The invention more particularly relates to an improvement whereby means are provided for reinforcing the usual wearing surfaces and relieving the knuckle pivot pin under pulling and buffing stresses.

Some of the objects sought and attained by the present construction are as follows:

20 1st: Increased strength and length of useful life of car couplers constructed in accordance with our invention under pulling and buffing stresses. 2nd: Increased strength of the knuckle in a line passing transversely through the center of the pivot pin hole.

25 3rd: Increase in effective strength and stiffness of the knuckle pivot pin by relieving it of a portion of the pulling and buffing stresses and a consequent decrease in the amount of wear of the pin and the pivot-pin holes both in the knuckle and in the lugs of the coupler head. 4th: Increase in total area of surfaces on the knuckle and head in contact during buffing stresses and by such increase to obtain a greater distribution of stresses and reduction of distortion. 5th: The construction of certain of the reinforcing surfaces in such manner that when the knuckle is opened the surfaces will not be in contact and will therefore offer no resistance to the swinging of the knuckle. These and further objects are attained in a construction such as shown in the accompanying drawings, wherein,

45 Figure 1 is a plan view of a knuckle constructed in accordance with our invention; Fig. 2 is a plan view of a coupler lug arranged to interfit with the knuckle shown in Fig. 1; Fig. 3 is a plan view of a complete coupler having our improvements applied thereto, and, Fig. 4 is a side elevation, partially broken away, showing the coupler and knuckle interfitted.

By the expressions "normal hub," "normal radius of hub," "normal hub diameter," etc., appearing in the specification and claims, we mean a hub, circular in outline, having a radius equal to the distance from the center of the pivot pin to the outer edge of the coupler lugs or ears; in other words, a hub as outlined by a circle whose center is the pivot pin center and whose radius is equal to the radius "j" in the accompanying drawings.

Referring to Fig. 1, it will be seen that the lug L is formed by arc a struck eccentrically from a point Q, close to but not coincident with the center O of the pin hole; by arc q, which is part of the contour of knuckle; by part of arc k; by radial line f, placed at r^2 ; from transverse center line Y, Y'; by radial line b, placed at s^2 ; from transverse center line Y, Y'; and, finally, by a portion of arc e and by line c, tangent to arc e, intersecting arc q at point of intersection of radial line b with arc c.

By experiment it has been found that with a force applied along the line F, F', at the point F', in the direction of the arrow head, as in pulling, and a resistance at T, T', in the direction of the arrow head, such as a coupler head, the resultant force passing through the knuckle pivot pin center, takes the direction A, A' approximately 45° from the line X, X'. Also by experiment it has been found that with a force applied along the line F, F', at the point F', in the direction of the arrow head at F, as in buffing stresses, and with a resistance applied at points E and G, in the direction of the arrows, as in a coupler head under buffing stresses, the resultant force through the knuckle pivot pin center has a direction of approximately 30° from the line X, X', such as the line B, B'.

By referring to Fig. 2, which is a plan view of the bottom ear of a coupler head (the top ear is similarly constructed), it will be seen that there is a corresponding depression to accept the lugs on the knuckle, surfaces b, c, and e, in this figure being those surfaces which come into contact with similarly marked surfaces of Fig. 1, during stresses due to buffing, while surface a of Fig. 2, comes in contact with surface a, of Fig. 1, during pulling. It will now be noted

that line A A' is normal to surface *a* of lug L, and that the width of lug L along this line is considerable, offering a high resistance to shearing during pulling stresses.

- 5 By referring to Figs. 1 and 2, it will therefore be seen that stresses in the direction of line A, A', will be resisted by surfaces *a* being in contact, and that such stresses will be taken up and distributed by the metal of the ears, thus relieving the knuckle pivot pin of the stresses tending to bend it in the direction of A, A', and rendering the coupler inoperative. Similarly, by referring to Figs. 1 and 2, it will be seen that stresses in 10 the direction of line B, B', will be resisted by surfaces *e*, being in contact, and the surfaces *e*, are normal to the direction of line of force B, B', and consequently are in the most effective position; also that a dimension of 15 lug L is very considerable measured along the line of force B, B'. Therefore the lug L is particularly well adapted to resist the stresses along this line, and such stresses will be taken up and distributed through the 20 metal of the coupler head, thus relieving the knuckle pivot pin of the stresses tending to bend it in the direction of B, B', and rendering the coupler inoperative.

Buffing stresses are further absorbed by 25 surfaces *b*, and *e*, of lug L of knuckle coming in contact with similar surfaces of coupler head, and by this added area of contact to reduce the rapidity of wear and consequent amount of distortion from the designed lines. The stresses are further taken up by selecting such a radius *d*, greatly in 30 excess of the normal radius *j*, (shown in dotted lines in Fig. 1) to describe arc *c*. Normal radius *j*, to generate an arc describing 35 the boundary of the hub of the knuckle is of the same length as distance from center of pivot pin hole O, to point *g* on contour, but radius *d*, as will be seen, is considerably greater than radius *j*, consequently the extent of surface *b*, and the strength of lug L 40 on the line B, B', also the strength on line and direction A, A', is greatly increased.

Transverse strength is gained by adding lug L to the top and bottom hub surfaces 45 (indicated at J, Fig. 4), of the knuckle so that the vertical distance (see Fig. 4) over said lug is increased by the total width of the lugs L. Therefore the strength of the knuckle under pulling stresses through a section Y, Y' is greatly increased. It has been 50 shown that in service coupler knuckles break very frequently through this section Y, Y', and this increased strength will very greatly reduce the failures of car couplers from this cause.

Surfaces *a* of knuckle and head, coming in contact during pulling stresses, offer an additional bearing and wearing area which serve to further distribute the stresses and to 55 thus maintain the designed contour lines and

consequently the useful life of the coupler for a greater period.

Surfaces *f* of knuckle and coupler head, coming into contact at the extreme limit of the outward or opening movement of the 70 knuckle, offer additional striking and bearing area to stop or limit the opening of the knuckle. The blow produced by the knuckle striking its stops in opening outward is thus absorbed and distributed through an increased area of surfaces, and thus further insures that the knuckle will not open to a point beyond that desired.

By constructing the knuckle and coupler head so that arc *a* is eccentric with the pivot 80 pin hole, the knuckle will swing away from and clear of arc *a* of the coupler head during the opening movement and there will be no interference of their surfaces to retard the opening or closing of the knuckle.

Surface G, heretofore referred to, assists 85 not only in absorbing shocks due to buffing but overcomes the tendency of the knuckle to move away from the guard arm under pulling stresses. This is explained because 90 of the tendency of the knuckle to rotate around its extreme inner end, which we have marked G'. Under pulling stress and with a loose pin, the resultant force in the line A, 95 A', will force the surfaces G into contact thus relieving the pin from all strain. Under buffing conditions, of course the surfaces G will act to absorb a portion of the stresses because of the tendency of the knuckle to 100 rotate on the surface E.

As a further protection against distortion due to buffing stresses, we have provided the flanges M, extending above and below the hub of the knuckle, these flanges being intended to contact the lug of the coupler 105 when the knuckle is closed. Preferably, the inner surfaces of these lugs are struck from a point eccentric to the pivot pin hole in order that they may contact the coupler lugs closely when the knuckle is in closed position and be free when swung outwardly.

We claim:

1. In a car coupler, the combination of a head having lugs, and a knuckle provided with reinforcements extending above and 115 below the hub thereof, said reinforcements consisting of integral lugs, an outer boundary line *e* of which is located outside of the normal hub contour and a radial boundary line *b* of which is located outside of a longitudinal line passed through the pivotal axis of the knuckle, substantially as described.

2. In a car coupler, the combination of a head having ears provided with recesses, a knuckle interfitting with said head and having 125 lugs adapted to coöperate with the recesses in said ears, said lugs extending above and below the knuckle hub and providing a substantial mass of metal outside the normal hub diameter which is intersected by 130

- lines indicating the resultants of forces applied in pulling or buffing, substantially as described.
3. In a car coupler, the combination of a head having ears provided with recesses, a knuckle, substantially arc-shaped lugs on said knuckle above and below the hub thereof, said lugs coöperating with the recesses in said ears, the arcuate extremities of said lugs forming stops, and being limited by radial lines extending from a point substantially coincident with the pivot pin center, the arc extending over more than 90° of the hub circumference, substantially as described.
4. In a car coupler, the combination of a head having ears provided with recesses, a knuckle interfitting with said head, lugs in said knuckle extending above and below the knuckle hub and adapted to coöperate with the recesses in said ears, said lugs providing a substantial mass of metal outside of the normal hub diameter, said mass of metal being so located as to be intersected by lines passing through the pivot pin opening at an angle of 45° and 30° respectively from the longitudinal center line of the coupler, substantially as described.
5. In a car coupler, the combination of a head having ears provided with recesses, said recesses forming abutments of substantial area, a knuckle provided with integral reinforcing lugs above and below the hub thereof, said lugs including a mass of metal outside the normal hub diameter, the bounding edges of said lugs being fixed by radial lines extending from the axis of the knuckle pivot and constituting stops of substantial area, said stops being adapted to contact said abutments and relieve the knuckle pivot pin of strains, substantially as described.
6. In a car coupler, the combination of a head having ears provided with recesses, a knuckle, lugs on said knuckle above and below the hub thereof, the outline of the outer portion of said lugs being formed partly from a radius substantially coincident with the pivot pin center and partly by a straight line tangent to said curved line, substantially as described.
7. In a car coupler, the combination of a head having ears provided with recesses, a knuckle, lugs on said knuckle above and below the hub thereof, the outline of the outer portion of said lugs being formed partly from a radius substantially coincident with the pivot pin center and partly by a straight line tangent to said curved line, and the inner surface of said lugs being curved on a radius eccentric to the pivot pin center, substantially as described.
8. In a car coupler, the combination of a head having ears provided with recesses, and a knuckle having an arcuate surface α and a substantially plane surface G co-operating with correspondingly shaped stops on the coupler head whereby to remove strain from the pivot pin by counter-acting the tendency of the knuckle to rotate about a point at or near the locking face of the knuckle, substantially as described.
